NECKTIE

Roger W. D. Beecher, 1510 Southridge Lane,
Cincinnati, Ohio

Filed Nov. 17, 1959, Ser. No. 58,372

Term of patent 14 years

(Cl. D3—16)

The figure on the drawing is a face view of a necktie showing my new design, the opposite face being conventional and unornamented.

The dominant feature of my design resides in the specific printed ornamentation shown on the small end of the necktie.

I claim:

The ornamental design for a necktie, as shown and described.
